(57) **CLAIM**

I claim the ornamental design for a chair, as shown and described.

DESCRIPTION

FIG. 1 is an isometric view of a chair of the present invention.

FIG. 2 is a side view of the chair of FIG. 1.

FIG. 3 is a front view of the chair of FIG. 1.

FIG. 4 is a rear view of the chair of FIG. 1.

FIG. 5 is a top view of the chair of FIG. 1; and,

FIG. 6 is a bottom view of the chair of FIG. 1.

The left side of the design is a mirror of the right side, so the left view has been omitted.
